ABSTRACT: An apparatus for discharging powder, flake, and other particulate materials has a bottom with an interior surface ascending to a central opening. A spreader above that opening has a larger radial width than that opening. The bottom and the spreader are provided with means for introducing air into the particulate material contained in the apparatus. Foreign particles are forced to the bottom and are monitored by electrical and magnetic detection means.

FIG. 1

FIG. 2

INVENTOR.
HANS A. ECKHARDT

APPARATUS FOR DISCHARGING PARTICULATE MATERIAL

This invention relates to apparatus for treating particulate material and in particular to apparatus for treating with a gas, drying, heating, aerating and fluidizing powdery or granular material in connection with the discharge of such material and with the detection and removal of foreign particles.

To treat powdery, granular or other particulate material with air or other gases for the purpose of drying or heating, bins, hopper, and other compartments containing such material are known which receive heated and dry air in their lower part and release it at their upper end. Usually these bins have at the lower conical end a central discharge opening and introduce the air at points above that opening, with the result that portions of the material receive considerably less air flow than others.

Since the air is introduced from the side, conical baffles are often used in the bin's lower part to distribute the air over the bin's circumference with the consequence that the flow of material in the lower part of the bin is detrimentally affected, often causing congestion and bridging in this area critical for uninterrupted discharge.

Other known devices attempt to solve the difficulties in connection with the discharge by vibrating the lower part of the bin together with a central baffle. While such equipment is suitable for discharging a variety of particulate materials, very sticky and tacky materials which tend to congest and bridge present severe difficulties, since they react adversely to vibration and compaction. Besides, these devices have not been designed for drying, heating and other gas contact operations.

Furthermore, the equipment mentioned above does not provide for the detection and removal of foreign particles which frequently get into the material accidentally during preceding production and handling operations. Such foreign particles often consist of steel, bronze, aluminum, and other metals, or of glass, ceramics, stone, etc. They have again and again caused severe damage to machinery further downstream, such as extrusion screws and liners, injection nozzles and molding dies, calenders and roll mills. Aside from the damage to processing equipment, foreign particles enclosed in end products have often made large production quantities unusable. The financial losses have been more severe by the lack of efficient methods to check extruded, molded or calendered products for enclosed foreign particles, and therefore the production over an extended period of time has often been scrapped when foreign particles were either actually enclosed or only suspected.

Apart from the above-mentioned bins for drying, heating and otherwise treating powdery or granular material, many attempts have been made to remove foreign particles from such materials. One approach is sifting the feed material through a screen upstream or downstream of the bin. This method involving an additional operation is only suitable for well-flowing materials, but not for tacky or sticky materials. Furthermore, only such foreign particles can be screened out which are larger than the largest particle size of the material to be processed. Very often the processed material particles are relatively large, as with polymer pellets, granulated chips, comminuted plastic products, and therefore foreign particles of comparable size can still damage equipment and even more so will cause the rejection of large production quantities.

Another method is the use of grate magnets upstream or downstream of the bin. It is obvious that only ferromagnetic particles can be expected to be removed. In the industry, however, stainless steel, bronze, aluminum and other nonmagnetic materials are largely used. Bolts, screws, nuts and other elements made of such metals sometimes come loose from equipment or get otherwise into the material flow. Furthermore, in many operations magnetized bars obstruct the flow of material excessively and therefore cannot be used. In addition, it has been found that even ferromagnetic bodies are not retained by the grate magnets, if the gravity forces overcome the magnetic forces. With electromagnets accidental switching on-off of the electric energy supply, even if for a short moment only,

has dumped the accumulated ferrous metal bodies together in the processing equipment, with even more severe consequences. Similar occurrences have taken place with permanent magnets after their magnetic fields had decreased below an effective level.

It is an object of the present invention to provide apparatus for treating particulate materials in a bin in such a manner that all portions of the material contained therein are uniformly dried, heated, aerated, fluidized or otherwise gas-treated, and to eliminate air baffles inverting the direction of air flow or restricting the material flow.

It is a further object to uniformly discharge difficult materials from the bin and to eliminate bridging, rat-holing and congestion.

It is a further object to reliably monitor and safely retain foreign particles in the bin.

Generally speaking, the present invention contemplates an improvement in an apparatus for drying, heating, aerating, fluidizing and otherwise gas-treating particulate material, comprising a bin or other compartment for receiving material, having a bottom with a central opening and an interior surface ascending to that opening which is located above the lowest portion of the bottom's interior surface. The compartment is provided in its lower part with means for introducing air or other gases into the material. Above the opening is positioned a spreader which has a larger radial width than the opening, the radial width increasing in downward direction. Sensing means based on principles of magnetism, electricity or radiation are provided to detect and to retain foreign particles in the compartment.

These and other features, advantages, objects and uses will become apparent by reference to the following description when taken in connection with the accompanying drawings showing preferred embodiments, wherein:

FIG. 1 is an elevational view, partly in section, of one embodiment of the apparatus; and

FIG. 2 is an elevational view, partly in section, of another embodiment of the apparatus.

Referring to the drawings, FIG. 1, there is shown an apparatus for treating particulate material with air or other gases. A compartment 10 for receiving material has a bottom 12 with a central opening 14 therein and an interior surface 16 ascending to the opening 14 which is located above the lowest portion of the interior surface of the bottom 12. A discharge duct 18 extends downward from the opening 14. The compartment 10 is provided in its lower part with means for introducing air or other gases into the material, comprising the gas-permeable plates 20, the covers 22 and the ducts 24 mounted in three sectorial sets between the radial ribs 26.

A spreader 28 positioned above the opening 14 has a substantially larger radial width than the opening 14 and has an increase in radial width in downward direction. The spreader 28 having a gas-permeable cone 30 is provided with means for introducing air or other gases into the material, including the gas-permeable tubes 32 holding the spreader 28 in position, the passageways 34 through the radial ribs 26, and the ducts 36. The latter elements are mounted as three sets at the three radial ribs 26 which form three rigid connections between the compartment 10 and the discharge duct 18.

The plates 20, the cone 30 and the tubes 32 are gas-permeable by using porous materials for their construction. Instead, gas-permeability can be achieved in other ways, for example, by using materials with perforations, woven cloth, screens or nozzles with filter screens providing openings for the gas smaller than the smallest particle size of the processed material.

The lower part of the compartment 10 is provided with magnetic means to pull magnetic particles to the interior surface 16 of the compartment 10. While permanent magnets and solid cores may be used, the magnetic means are shown as comprising laminated cores 38 with primary windings 40, and secondary windings 42 mounted in three sets between the three radial ribs 26.

The primary windings 40 induce into the secondary windings 42 a voltage changed by foreign particles changing the magnetic field, the change in voltage being used for indicating the presence of such foreign particles by a millivoltmeter 44 of other voltage or current indicating means.

The laminated cores 38 form part of the interior surface 16 of the compartment 10 and have the odd numbers of insulated laminae electrically connected to the compartment 10 and to one pole of a battery 46 or another electric energy source of which the other pole is electrically connected to the even numbers of insulated laminae via a switch 47 and a signal light 48 or other current indicating means for signaling the presence of electrically conductive particles bridging the space between any even and any odd numbers of laminae and the compartment 10.

In the lower part of the compartment 10 access doors 50 are provided for easy access to the interior surface 16 of the compartment 10, and above the access doors 50 shutoff gates 52 are provided to open and close the flow of material toward the opening 14. These elements are also mounted in three sectorial sets.

For such particulate materials which make a circular manner of gas agitation and discharge desirable, similar to a cyclone or a whirlpool, the means for introducing air or other gases into the material are controlled to admit the gas to the compartment 10 in a circumferentially timed sequence. Such a sequence can be achieved by pneumatic control means which are conventional and not shown.

Furthermore, there may be provided means for vibrating the bottom 12 and the spreader 28 in horizontal or other directions, when treating such particulate materials which react advantageously to vibration. Conventional means for vibrating may be employed and is shown at V. Advantageously the magnetic means for pulling magnetic particles to the interior surface 16 of the compartment 10 may be used for vibrating the bottom 12 and the spreader 28, and since magnetic means for vibrating purposes are known, such conventional arrangements are not shown.

In operation, powder, flake, beads, granules, pellets, chips or other particulate material received by the compartment 10 is fluidized by air or other gases introduced through the gas-permeable cone 30, tubes 32 and plates 20 so that the material flows similarly to a fluid over the cone 30 to the bottom 12 and over the opening 14 into the discharge duct 18.

The air is preferably supplied heated or dried or both to perform a heating or drying operation or both in the compartment 10, using conventional means for heating or drying the air (not shown). The air flows in an upward direction to the top of the compartment 10 where it is removed to atmosphere, to an exhaust, or to a vacuum pump after having passed a cyclone or other filter (not shown).

The material is fluidized to such a degree that heavier foreign particles, whether ferromagnetic or not, whether electrically conductive or not, achieve sufficient freedom of movement to be forced down by gravity to the bottom 12. They remain there since they have no tendency to pass the ascending surface 16 to the opening 14. Light foreign particles having even a high ratio of surface to weight, like steel shavings with ferromagnetic properties, are pulled toward the laminated cores 38. Even before reaching them, ferromagnetic particles as well as other foreign particles cause a change in the voltage induced in the secondary windings 42, measured by the millivoltmeter 44 or other means for indicating a change in voltage or current.

When ferromagnetic or other conductive particles reach the laminated cores 38, they bridge the space between the even numbers and the odd numbers of laminae and surrounding portions of the surface 16, and cause a current to flow, with the switch 47 closed, through the signal light 48 or other means for indicating a change in current.

To remove foreign particles accumulated at the bottom 12 without emptying out the entire material from the compartment 10, the shutoff gates 52 are pushed inward to the

spreader 28, thus closing off the flow of material from the upper part of the compartment 10 to the opening 14. Then easy access to the interior surface 16 is facilitated through the access doors 50.

FIG. 2 shows a different embodiment of the apparatus. A compartment 110 for receiving material has a bottom 112 with a central opening 114 therein, the interior surface 116 ascending to that opening 114 which is located above the lowest portion of the interior surface of the bottom 112. A discharge duct 118 extends downward from the opening 114.

The compartment 110 is provided in its lower part with means for introducing air or another gas, comprising the perforated plates 120, the covers 122, and the ducts 124 mounted in three sectorial sets between the three radial ribs 126.

A spreader 128 positioned above the opening 114 has a substantially larger radial width than the opening 114 and has an increase in radial width in downward direction. The spreader 128 is mounted rotatably by the shaft 129, the bearing 132, the three brackets 131, and drive means further above (not shown). The spreader 128 is connected with an agitator 133 having an element 134 extending from the outward portion of the spreader 128 in an outward and upward direction. The other elements of the agitator 133 are designated 135, 136, 137. Two additional sets of agitators spaced 120° apart are not shown.

The spreader 128 is provided with means for introducing air or other gases into the material, comprising a bore 138 in the shaft 129, perforations in the spreader 128 and a cloth 139 covering these perforations. The openings in the cloth 139 are smaller than the smallest particle size of the processed material.

In the lower part of the compartment are positioned electrically conductive members 143 which are in contact with the processed material, electrically insulated from the compartment 110 and electrically connected via a switch 147 and a signal light 148 or other current indicating means to one pole of a battery 146 of which the other pole is electrically connected to the compartment 110. The signal light 148 signals the presence of electrically conductive particles bridging the distance between any of the members 143 and the perforated metal plates 120 and other portions of the interior surface 116.

Gas-permeable plates 120 which are electrically nonconductive, for instance, of porous ceramics, can be used, if the members 143 with odd numbers are electrically connected to the compartment 110 and to one pole of the battery 146 of which the other pole is electrically connected to the members 143 with even numbers which are electrically insulated from the compartment 110. The signal light 148 then signals the presence of electrically conductive particles bridging the distance between members any of the even numbers and any of the odd numbers of the members 143 and the compartment 110.

While the compartment 110 is shown as being equipped with means for sensing foreign particles, the compartment 110 may carry one part and the spreader 128 another part of sensing means for detecting foreign particles. These sensing means may be based on principles of magnetism, electricity or radiation, or combinations thereof.

In operation, powder, flake or other particulate material received by the compartment 110 is fluidized by air or other gases introduced through the perforated conductive plates 120 and the cloth 139, so that the material flows similarly to a fluid over the spreader 128 to the bottom 112, and over the opening 114 into the discharge duct 118.

The material is fluidized to such a degree that heavier foreign particles, whether ferromagnetic or not, whether electrically conductive or not, achieve sufficient freedom of gravity movement to settle down at the plates 120 and surrounding portions of the bottom 112. They remain there since the surface 116 ascending to the opening 114 serves as a flow weir.

When electrically conductive bodies reach the bottom 112, they usually are sufficiently large to bridge the distance

between the conductive perforated plates 120 and the conductive members 143. With the switch 147 closed, they cause a current to flow through the signal light 148. Single conductive particles which are too small to bridge that distance will not alarm the operator, but if large numbers accumulate, they will form a conductive bridge. Principally, the size of conductive foreign particles which are to cause a signal can be easily predetermined by choosing the distance between the members 143 and the plates 120.

Primarily for such particulate materials which react advantageously to mechanical agitation and are usually somewhat tacky, sticky or cohesive, the agitator 133 is provided. The elements 134, 135, 136 cut out of the material a ring of triangular cross section which gradually sinks down toward the bottom 112 at the same time being sliced into thin horizontal layers by the element 136. Into the area thus being vacated sinks an upper ring of material with a cross section determined by the spreader 128, the shaft 129 and the members 134, 137, and this ring is being shaved in the form of thin layers by the member 134 into the space being vacated. Into the space vacated by that upper ring of material sinks down the material from the upper part of the compartment 110, also sliced into thin layers by the member 137.

The agitator 133 is provided with a larger distance to the tapered sidewall of the compartment 110, when the spreader 128 is mounted for axial movement to vary the flow cross section between the opening 114 and the spreader 128. In the lowest position the spreader 128 covers the opening 114 and thus serves as a bottom closure of the compartment 110. The compartment 110 can then be emptied, for instance, after removing the covers 122 and plates 120.

In order to shut off the flow from the upper portion of the compartment 110 to the bottom 112 between the periphery of the spreader 128 and the tapered sidewall of the compartment 110, the spreader 128 is equipped with a radial width sufficiently large that in its lowest position it contacts the tapered sidewall of the compartment 110. In the area of this circumferential contact line the sidewall of the compartment 110 is preferably more tapered toward the horizontal plane. With the spreader 128 in this lowest position, the covers 122 and the plates 120 can be removed, preferably by hinge connections, for inspection and cleanout, with the compartment 110 full all the way above that circumferential contact line.

Although the present invention has been described in conjunction with particular embodiments, it is apparent to those skilled in the art that modifications and variations are possible without departing from the spirit and scope of the invention. For instance, the opening and the spreader may be off center of the compartment; the axis of the compartment or of the spreader or both may be tilted from the vertical position; more than one opening and spreader may be applied; the odd numbers of laminae and of electrically conductive members may be exchanged against the even numbers and vice versa; various types of baffles may be used to improve the flow of air and of the material; besides air, other gases may be applied, especially when certain reactions are to be performed or prevented, respectively, such as reducing, oxidizing, calcining, activating, or purging with an inert gas.

In the described embodiments surfaces are shown to be provided for sealing against gases and the material. The seals, however, are not shown because of their size and for better clarity. Also not shown are bolts, screws, nuts to connect parts shown as being provided with flanges for such connections.

Such modifications and variations are considered to be within the purview and scope of the invention and appended claims.

I claim:

1. Apparatus for discharging particulate material comprising a compartment for receiving material in the interior thereof having a bottom extending over the larger and peripheral portion of the horizontal cross section through and inside of the compartment interior's lower end V and a central

opening therein through which the particulate material discharges downward, the central opening having a horizontal dimension which is larger than one-tenth of the horizontal dimension of said bottom projected to the horizontal plane through the upper end of said opening, the interior surface of said bottom ascending with angles of less than 90° to the horizontal in a continuous, unbroken and smooth ascent to said opening which is located above the lowest portion of said interior surface.

10 2. Apparatus for discharging particulate material as claimed in claim 1 wherein the bottom forming a continuous, unbroken and smooth interior surface in the inclined ascent to the opening is made of gas-permeable material over more than one-eighth of the interior surface of said bottom and is provided with means for introducing a gas through said gas-permeable material into the compartment.

15 3. Apparatus for discharging particulate material as claimed in claim 1 wherein a spreader is positioned in its entirety above the opening and above at least a portion of the smoothly and continuously ascending bottom surface and comprises a nonperforated substantially horizontal plate with a horizontal dimension which is between 5 and 150 percent larger than the horizontal dimension of the opening, and a cone connected with its large circumference to said nonperforated plate and decreasing in upward direction in radial width.

20 4. Apparatus for discharging particulate material as claimed in claim 3 wherein the spreader is attached to a vertical shaft mounted rotatably and is connected with an agitator having an element extending from the outward portion of said spreader in an outward and upward direction to a point near the interior compartment wall, and a second element extending from said point inward to said shaft, so that the material outside and under said element is separated by said agitator from the material inside and above said element.

25 5. Apparatus for discharging particulate materials as claimed in claim 3 wherein between the horizontal plate of the spreader and the continuously ascending bottom at least two substantially vertical members are provided, at least one member having a conduit and being provided with means for introducing a gas between the cone of the spreader increasing in radial width in downward direction, and the spreader's plate extending substantially in horizontal direction and forming with said cone an angle of less than 90°, into the compartment, the surface of the cone being smooth, unobstructed and comprising gas-permeable material.

30 6. Apparatus for discharging particulate material as claimed in claim 3 wherein the bottom of the compartment ascends over an interior surface area larger than the vertical downward projection of the spreader covers, to the central opening continuously and smoothly with an angle of less than 90° to the horizontal, and means for vibrating said bottom and said spreader are provided.

35 7. Apparatus for discharging particulate material as claimed in claim 3 wherein the spreader with a substantially horizontal plate surface is axially moveable to the opening's upper rim to decrease the flow of material, and is axially moveable from said rim to increase the flow of material.

40 8. Apparatus for discharging particulate material as claimed in claim 7 wherein the spreader in its lowest position closes the flow of material across a circumferential line formed between the substantially horizontal plate surface of said spreader and said openings upper rim.

45 9. In an apparatus for discharging particulate material comprising a compartment for receiving material having a bottom with a central opening therein and an interior surface ascending to said opening which is located above the lowest portion of said interior surface, the improvement therein comprising an access door provided in the lower part of the compartment for easy access to the interior surface of said compartment and a shutoff gate above said access door to open and close the flow of material toward said opening.
